[57] CLAIM

The ornamental design for a cash and credit card actuated terminal for controlling the dispense of motor fuel or similar article, as shown and described.

DESCRIPTION

FIG. 1 is a front perspective view of a cash and credit card actuated terminal for controlling the dispense of motor fuel or similar article, showing my new design;

FIG. 2 is a front elevational view thereof;

FIG. 3 is a right side elevational view thereof, the left side being a mirror image thereof; and

FIG. 4 is a rear elevational view thereof.

The top plan view is plain and unornamented.

FIG. 1

FIG. 2

FIG. 3

FIG. 4
